1933, Serial No. 677,798

11 Claims. (Cl. 196—46)

My invention relates to an apparatus adapted for carrying out the process, set forth in an application filed by me and which has issued as Patent 2,006,407, July 2, 1935, for chemically 5 treating topped crude oil to prepare it for distillation into its various lubricating fractions. Of said application this application is a division.

In the distillation of lubricating oils from topped crude oil it is of the utmost importance to free 10 the stock charged to the lubricating oil still from any impurities which may be therein contained and which are the results of cracking or oxidizing a portion of the crude while topping the same. Such cracked or oxidized compounds, if permitted 15 to remain in the charging stock, will ultimately vaporize with the lubricating oil fractions during distillation, thereby making such lubricating oils unfit for sale without extensive chemical treatment, as the cracked or oxidized com- 20 pounds greatly impair the color, odor, etc., of the distilled oil. It is also of the greatest importance to remove any water, whether naturally present in the crude or added thereto in processes for treating it to prepare it for distillation.

25 As some crudes are received from the wells they contain, among other impurities, sodium, magnesium, and other chlorides. Some of these chlorides are removed in solution when the water originally contained in the crude is settled out, but a small proportion of them will remain in the crude. When the topped crude is subsequently treated with alkali solution to remove cracked and oxidation products, the alkali used is a com- 30 mercial form containing impurities in the form 35 of chlorides. If the topped crude is not thor- 40oughly dehydrated after the alkali treatment, serious harm is likely to result, as the water together with the naturally present and added chlorides react, at the temperatures required to 45 distill lubricating oils, to form hydrochloric acid. This acid is extremely corrosive to the metal of the stills and for this reason all water must be removed, for without it the chlorides cannot form hydrochloric acid and have no deleterious action 50 on the stills. It is necessary to treat the topped crude with an aqueous solution of alkali in order to get a complete mixture and contact between the oil and alkali. If alkali in solid or com- 55 minated form is added to the oil, a complete mix- ture cannot be effected and the alkali settles out onto the heating surfaces of the stills, thereby in a short time impairing heat exchange to such an extent that the stills must be shut down for cleaning.

55 A patent issued to me November 24, 1931, No.

1,833,691, and an application filed by me which has issued into Patent 1,903,407, Apr. 4, 1933, are both directed to processes for dehydrating, topping, and then treating crude oil with an alkali solution in order to prepare the crude oil for distillation of the various lubricating fractions contained therein. The present application is directed 5 more specifically to an improved apparatus for treating the topped crude oil with sodium hydroxide or other alkali solution and is especially 10 adapted for the practice of the process forming the subject-matter of my Patent 2,006,407.

By means of my improved apparatus I may 15 treat the topped crude or mazoot by thoroughly mixing the same with sodium hydroxide solution to convert some of the cracked or oxidation products present into complex high boiling compounds, mainly soaps, which will not vaporize at subsequent distillation temperatures and to precipitate other cracked or oxidation products as 20 sodium salts. I am also able to completely remove the water, which is introduced as a solvent for the sodium hydroxide, from the mazoot before distillation of the contained lubricating fractions. I am also able to remove, from the alkali- 25 treated topped crude, all decomposition products which are precipitated by the alkali treatment and subsequent dehydration.

In the drawing:

Fig. 1 is a front elevation with a section of the 30 tower cut away;

Fig. 2 is a section of the tower on line 2—2 of Fig. 1.

The heated topped crude or mazoot is continuously pumped to the mixing and evaporating 35 tower 3 through line 1. The crude, of which this mazoot is a residuum, is first freed of its contained salt water by heating and settling under pressure after which it is further heated in a pipe still, and the lighter constituents, such as 40 gasoline, kerosene, and gas oil, vaporized in a distillation tower. The bottoms from this distillation tower, which comprise the mazoot to be treated by the present invention, leave the distillation tower and are pumped to the apparatus 45 herein described at a temperature of 500° to 575° F.

The heated mazoot continuously enters the mixing pan 4 in tower 3, tangentially thereof, so as to give it a whirling motion and is therein 50 mixed, for example, with 1% of 38 Bé. sodium hydroxide solution, which is pumped through line 2 and forced downwardly into the whirling mazoot. As the mazoot-soda mixture overflows from the pan 4 it cascades over the series of 55

trays 5 and 6, which are supported on the uprights 7. These uprights 7 also support the pan 4. As the mazoot-soda mixture cascades over the trays 5 and 6 the water, which acted as solvent for the caustic soda, is vaporized, and some light oil fractions may also be vaporized with the water. Due to the high temperature of the mazoot (500°-575° F.), the tower 3 may be maintained under a pressure above or below atmospheric or may be maintained at atmospheric pressure. However, since it is usually desired to evaporate as much of the water (soda solvent) and as little oil as possible in the tower, the best working pressure can be determined from these factors. The water and oil vapors pass upwardly through the tower 3 and then through line 8 to a condenser and separator (not shown). Safety valve 9 is provided at the top of the tower to prevent the pressure from rising above any predetermined point.

The soda-treated mazoot passes downwardly from the bottom of the tower through throat 10 to one end of a settling chamber 11 through which it flows to the opposite end whence it passes through cross-over line 12 to one end of settling chamber 13. At the opposite end, settling chamber 13 is connected to a third settling chamber 15 by cross-over 14. After flowing through chamber 15 the treated mazoot passes out of the system through line 16.

Vapors are formed within the three settling tanks which, if permitted to accumulate within the tanks, would by their pressure lower the level of the liquid within the tanks to a point below the cross-over lines 12 and 14, thereby preventing an even flow of mazoot. For this reason tanks 13 and 15 are provided with domes 17 and 18 respectively, which are connected to pressure equalizing line 21 by pipes 19 and 20 respectively. Any difference in pressure within the three tanks is equalized by the line 21. Connections 22 and 23 are placed between line 21 and vapor line 24, which conveys any vapors generated within the tanks to the top of the tower 3. The provision of vapor line 24 obviates the necessity of the vapor passing into the throat between tower 3 and tank 11 and then up against the downwardly flowing soda treated mazoot. At times the settling mazoot may foam due to the rapid formation of vapors in the settling tanks, in which case the foam passes over pipe 21 to the throat between tower 3 and tank 11 and is beaten down by the falling mazoot.

During the passage of the soda treated mazoot through the settling tanks 11, 13 and 15 certain sodium salts, formed by the action of the caustic soda on the cracked and oxidation compounds present in the topped crude, are precipitated. These sodium salts settle to the bottoms of the tanks and are drawn off at intervals through valved outlets 25, 26 and 27, at the center of the respective tanks. Each of these outlets is connected to a manifold 28, which in turn is connected to pump 40 by line 39. These sodium compounds are of such a nature that they are liable to pack solidly in the bottoms of the tanks 11, 13 and 15 and thereby stop up the outlets 25, 26 and 27. For this reason there are provided two other draw-off pipes in each tank, one draw-off being positioned at each end of the tank. These draw-offs extend downwardly from near the top of the tank to within a few inches of the bottom so that there is no likelihood of their being stopped up by tightly packed sludge. The draw-offs just described, which are placed in the

front of the settling tanks, are numbered 29, 31 and 33. Draw-offs 29 and 31 are connected to pipe 41, which is provided with valves for controlling the flow from each tank. Pipe 41 is connected to pump 40 by lines 35, 37 and 39. The front draw-off 33 in tank 15 is connected to pump 40 by lines 42, 43, 35, 37 and 39. This draw-off is also provided with a valve in line 42 to regulate the outflow of sludge. The rear draw-offs are located directly to the rear of the front draw-offs and are numbered 30, 32 and 34. These draw-offs are also provided with control valves and connecting lines to pump 40. Line 36 corresponds to line 35 in the front draw-off system and connects through lines 37 and 39 to 15 pump 40 while lines 45 and 46 correspond to lines 42 and 43 in the front of the tank. It is readily seen that with the arrangement just described, any one sludge draw-off may be used if more sludge should collect in any one tank than in 20 the others, or all sludge draw-offs may be used at once.

The oil is thus thoroughly dehydrated, thereby preventing the formation of hydrochloric acid, the destructive effects of which have been here- 25 before explained.

It has been specified herein, by way of an example, that 1% of 38° Bé. caustic soda solution is admixed with the mazoot. The necessary amount of the soda, however, varies with different crudes. The caustic soda is not added to treat the mazoot solely in the step of preparing mazoot for distillation into lubricating oils herein described, but is also added so that there will be a surplus of free alkali left in the oil to react 35 with any cracked or oxidation compounds which may form during the actual distillation. For this reason enough caustic soda is added, in the process herein described, so that about 2% of free alkali remains in the asphalt bottoms after the 40 lubricating fractions have been removed or distilled off. The free alkali left in the topped crude is so finely divided, due to the intimate mixture possible when it is added in aqueous solution, that it will not settle out onto the heating 45 surfaces of the stills.

It is ordinarily desirable, in tower 3, to vaporize only the solvent (water) of the alkali. However, some light oil fractions are likely to evaporate with the water; and it may be desirable, 50 under some conditions, to vaporize in the tower, in addition to the water, an intermediate or final cut of gas oil or a light fraction of lubrication oil.

What I claim and desire to protect by Letters Patent is:

1. Apparatus for alkali treatment of topped crude oil comprising a tower and a settling tank, a mixing pan within the tower, oil and alkali solution inlets to the pan, a series of trays also within the tower but below the mixing pan, a vapor outlet from the tower above the pan, an oil passage from the tower to the settling tank, a sludge outlet from the settling tank and an oil outlet from the settling tank.

2. Apparatus for alkali treatment of topped crude oil comprising a tower and a plurality of settling tanks, a mixing pan within the tower, oil and alkali solution inlets to the pan, a series of trays also within the tower but below the mixing pan, and a vapor outlet from said tower above 60 the pan, a passage for treated oil from the tower to the settling tanks, means for equalizing the vapor pressures in the tanks, sludge outlets from the settling tanks and oil outlets from said settling tanks.

3. Apparatus for alkali treatment of topped crude oil comprising a tower and a plurality of settling tanks arranged in series, a mixing pan within the tower, oil and alkali inlets to the pan, 5 a series of trays within the tower but below the pan, a vapor outlet from the tower above the pan, a treated-oil passage from the tower to the first of the series of settling tanks, treated-oil passages between the settling tanks, an outlet 10 for treated oil from the last tank in series, and sludge draw-offs from the settling tanks.

4. Apparatus for treating topped crude oil preparatory to distillation of lubricating oils, which comprises an evaporating tower wherein 15 the solvent of the alkali of a mixture of oil and an alkali solution is adapted to be vaporized, a series of settling tanks through which the treated mixture is adapted to successively flow, means affording an oil flow passage from the evaporating 20 tower to the first tank of the series, outlets for settled sludge from each tank, an oil outlet from the last tank of the series, vapor outlets from the settling tanks beyond the first tank of the series, and a vapor line connecting said outlets 25 with said passage.

5. Apparatus for alkali treatment of topped crude oil comprising a solvent evaporating tower; a plurality of settling tanks arranged in series; a vapor outlet from the tower; a passage for 30 treated oil from the tower to the first of the series of settling tanks; passages for treated oil between the settling tanks; and a plurality of sludge draw-offs from each tank, one draw-off having an inlet opening into the bottom part of 35 the tank and extending therefrom through the tank bottom and through which solids are adapted to be drawn off at intervals and another draw-off having an inlet end opening into the tank above its bottom and extending therefrom upward, and pumping means for forcibly removing sludge from the last named draw-offs.

6. Apparatus for alkali treatment of topped crude oil comprising a solvent evaporating tower, a plurality of settling tanks arranged in series, 45 a vapor outlet from the tower, a treated-oil passage from the tower to the first of the series of settling tanks, treated-oil passages between the settling tanks, a treated-oil outlet from the last tank in series, sludge draw-offs from the 50 settling tanks, and vapor passages establishing communication between the said oil passage, the settling tanks and the upper part of the tower.

7. Apparatus for settling precipitated matter from alkali treated topped crude oil comprising a 55 plurality of tanks so connected that the oil containing the material to be settled flows from end to end of each tank and then to the next tank in series; an oil inlet to the first tank of the series; an oil outlet from the last tank of the series; sludge draw-offs, one draw-off having an inlet 60 opening into the bottom part of the tank and extending therefrom through the tank bottom and

through which solids are adapted to be drawn off at intervals and another draw-off having an inlet end opening into the tank above its bottom and extending therefrom upward, and means for equalizing the vapor pressure within the tanks. 5

8. Apparatus for settling precipitated matter from alkali treated topped crude oil comprising a plurality of tanks so connected that the oil containing the material to be settled flows from end to end of each tank and then to the next tank in 10 series; an oil inlet to the first tank of the series; an oil outlet from the last tank of the series; sludge draw-offs, one set extending downwardly from the bottom of each tank and another set extending upwardly from near the bottom of each 15 tank; means for removing vapors generated in the tanks; and means for equalizing the vapor pressures within the tanks.

9. Apparatus for treating topped crude oil preparatory to distillation of lubricating oils, which 20 comprises an evaporating tower wherein the solvent of the alkali of a mixture of oil and an alkali solution is adapted to be vaporized, a settling tank adapted to receive from the tower the dehydrated mixture and provided with an outlet for oil and 25 an outlet for settled sludge, a vapor offtake from the evaporator and a vapor offtake leading from the settling tank to a point in the evaporator above the locus therein of vaporization of said solvent.

10. Apparatus for treating topped crude oil preparatory to distillation of lubricating oils, which comprises an evaporating tower wherein the solvent of the alkali of a mixture of oil and an alkali solution is adapted to be vaporized, means 35 to separately admit the oil and the alkali solution to a locus of mixing within the tower, a settling tank adapted to receive from the tower the dehydrated mixture and provided with an outlet for oil and an outlet for settled sludge, a 40 vapor offtake from the evaporator and a vapor offtake leading from the settling tank to the evaporator at a level therein above that of the points of admission thereto of the oil and the alkali solution.

11. Apparatus for treating topped crude oil preparatory to distillation of lubricating oils, which comprises an evaporating tower wherein the solvent of the alkali of a mixture of oil and an alkali solution is adapted to be vaporized, a 50 settling tank, into which hydrated oil is adapted to flow from the tower, said settling tank being provided with a low outlet for withdrawal of settled sludge, an oil outlet and a vapor outlet above the oil outlet, a pipe connected with the 55 vapor outlet and through which any oil foam carried off with the vapors through said vapor outlet is adapted to be conveyed to the oil stream from the tower and thus returned to the settling tank, and a vapor pipe adapted to carry off vapor escaping from said vapor outlet.
